UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

ODOMETER.

1,169,175.

Specification of Letters Patent. Patented Jan. 25, 1916.

Application filed October 12, 1912. Serial No. 725,423.

To all whom it may concern:

Be it known that I, RAY H. MANSON, a citizen of the United States, residing at Elyria, in the county of Lorain and State of Ohio, have invented certain new and useful Improvements in Odometers; and I do hereby declare the following to be a full, clear, and exact description of the invention, such as will enable others skilled in the art 10 to which it appertains to make and use the same.

My invention disclosed in this application relates to odometers or registering mechanism which are more particularly intended 15 to register the mileage traversed by automobiles and similar vehicles. In the use of such vehicles, it is highly desirable to have a means for registering the mileage of a particular trip or a particular day's mileage. 20 In order to insure the success of such an instrument, one should be able to restore the registering means to any desired point such as the beginning of the trip.

I aim to provide such a trip register and 25 means for enabling the driver to restore the register to any desired indication at any time he desires, providing of course, that the trip register is capable of registering such 30 indication. In using the terms "any desired indication," etc., it is understood that such terms are used with this meaning. I aim to provide such a device as will most readily lend itself to use in connection with guide 35 books or road maps, such as used by motorists, or if the various points along a route are marked in terms of the mileage from a given starting point. In the device of my 40 invention even if the motorist takes up a route intermediate of its ends he can by reference to some known land mark indicated in such book or map set his trip register exactly in accordance therewith and proceed on his way, the register thereafter corresponding with his book or map indications. 45 I am aware that devices having this general purpose have hitherto been provided, but they have been constructed in such a way that it was necessary to employ a plurality of devices for operating the 50 instrument.

It will be seen by reference to my detailed description and to the drawing illustrating an embodiment of my invention, that I have there controlled the device through one in-

strument which can be operated by one of 55 the hands of the driver.

Other objects of my invention and the invention itself will be better understood by reference to the description of the particular embodiment illustrated in the drawing. 60

Figure 1 is a plan view of a device illustrating my invention, and in which some of the parts are shown in section. Fig. 2 is an elevation of certain of the parts shown in Fig. 1. Figs. 3 and 4 illustrate details of 65 the embodiment shown in Figs. 1 and 2.

Referring now to the drawing and to the embodiment of my invention illustrated therein, at 1 I show a base plate for supporting apparatus. At 2 is shown the means for 70 registering the mileage or whatever else it is desired to measure. The device 2 consists of a plurality of wheels 3, 4 and 5, one of which is connected to a ratchet wheel 6 adapted to be associated therewith in such a 75 way as to drive the wheel 5. I have here shown a ratchet wheel, though any suitable device for this purpose may be employed. The wheels 3, 4 and 5 bear scales and are associated with each other in any of the 80 well known ways, so that motion can be communicated from one to the other at the proper and desired time.

Suitable means are provided for driving the pawl wheel 6. I here show a driving 85 pawl 7 which is driven through a shaft 8, a gear wheel 9 and a worm gear 10, mounted on a shaft 11, which is driven by the wheel of the automobile or other vehicle. The pawl is mounted upon an eccentric of the 90 wheel, so that it is reciprocated when the shaft 8 is rotated. This construction is well known and has not been illustrated in detail here.

I provide suitable means for holding the 95 ratchet wheel into a driven position, that is, for example, in the form illustrated into the position into which it has been driven by the pawl 7. In the form shown I employ a holding pawl 12, which is pivoted at 13 to any suitable part, such as the frame or base plate 1. Means are provided for holding the pawls in engagement with the ratchet wheel. A spring is suitable for this purpose, and I have here illustrated a spring 14 which may 100 be connected to the pawl and to any suitable member. I find it most convenient to connect this spring at one end to each of the

pawls, since I have illustrated them on opposite sides of the wheel.

As will be seen, when the shaft 11 (see Fig. 2) is rotated, the registering mechanism 5 will be driven from the pawl 7 on the ratchet wheel 6 and held in such driven position by the pawl 12. Assuming now that it is desired to reset the trip register, or return it to zero position, I provide means for releasing the registering mechanism from the control exercised over it by the previously described mechanism, and assuming an independent control thereof, and in the form shown, I employ a single device which 10 controls the mechanism governing both these operations.

A lever 20 is pivoted at 21 to a suitable portion of the frame. This lever carries a fork 22 on one end which engages a groove 23 upon a sliding member 24. The lever 20 also controls a cam 25 which is here shown as formed upon a portion of the lever, bent out at substantially right angles thereto and constituting a portion of the material originally inclosed within the fork 22. The cam 25 preferably carries two cam surfaces 27 and 28 upon the opposite sides thereof. These surfaces engage the pawls 7 and 12, camming them away from engaging position with the ratchet wheel when the lever 20 is moved inward. I also provide suitable means for assuming control over the registering device when the same has been disengaged from the pawl. In the form 30 shown, this consists of a plurality of openings or slots 30 which may be formed on the registering device and preferably upon the ratchet wheel 6. These slots or openings may be engaged by some member, such as a 35 projection 31 upon the member 24. In the form shown, the member 24 consists of a plunger 32 having a knurled portion 33 which may be engaged by the fingers and rotated. When it is desired to reset the 40 trip register, the plunger 32 is forced inward, sliding in the opening 40 in the nipple 41. This forces the member 20 inward, driving the cam 25, prying the pawls away from the ratchet wheel, releasing the registering mechanism therefrom and at the same 45 time forcing the projection 31 into one of the openings 30 in the ratchet wheel, so that when the member 32 is rotated, the registering mechanism will be operated, enabling it to be set to any given registration by turning it in either direction. It is desirable 50 that it should be rotatable in either direction when being reset, because much time may be saved when the registering mechanism is near the desired point by turning it 55 backward or forward to that limit at the will of the operator. The lever 20 is held in its normal position by the pawls 7 and 12 which in turn are retained in position by 60 the spring 14. These constitute the means 65

tending to hold the member 20 and also therefore the engaged plunger 32 in normal position. If desired, any other suitable means may be provided for holding the lever 20 in its normal position as illustrated in the drawings. This member 20 may consist of any suitable device. I have illustrated it as a lever for convenience. I may also hollow out the plunger 32 as shown at 50 and provide a guide 51, as illustrated in the drawing. It will in fact, be apparent to those skilled in the art that numerous and extensive departures may be made from the form and details of the instrument illustrated. I have shown this embodiment simply for the purpose of illustrating the invention, and not with any intention of being limited thereto, since the scope of the invention is set forth in the appended claims.

I claim—

1. In an odometer, the combination of registering means, driving mechanism therefor, including a ratchet wheel and a driving pawl adapted to drive the registering means to any one of a plurality of positions, holding means for the registering means including a holding pawl and teeth on the ratchet wheel, apparatus for releasing the ratchet wheel from the pawls and assuming control thereof independently of the pawls including a pivoted lever provided with a cam for camming the pawls away from the ratchet wheel, and a manually operable sliding member to engage the ratchet wheel to operate the same.

2. In an odometer, the combination of registering means, including rotary reference carrying members, a ratchet wheel associated with the registering means, mechanism for driving said registering means, including a driving pawl and teeth on the ratchet wheel, mechanism for holding said registering means in driven position including a holding pawl and teeth on the ratchet wheel, apparatus for removing said registering means from the control of said driving mechanism and said holding means, including a cam adapted when operated to move said pawls from engagement with the teeth on the ratchet wheel, means to assume control of said registering means when the pawls have been disengaged from the ratchet wheel and a device for operating both the cam and the last named means to move the registering means in either direction when it has been released from the pawls.

3. In an odometer, the combination of registering mechanism including a ratchet wheel, a driving pawl and a holding pawl therefor, a lever carrying a cam for releasing said ratchet wheel from said pawl, said ratchet wheel being provided with a plurality of slots, a plunger controlling said lever to move said cam to engage said pawls to release said ratchet wheel from said pawls

and a catch on said plunger for engaging one of the slots in the ratchet wheel and adapted to drive the same independently of the pawls to cause said registering mechanism to show any desired indication.

4. In an odometer, the combination of registering means, including rotary reference carrying members and a ratchet wheel, a driving and a holding pawl, a lever pivoted in said odometer, a cam member on said lever projecting at an angle from said lever, said cam member carrying two cam surfaces adapted to engage said pawls to disengage

them from the ratchet wheel, said ratchet wheel being provided with a plurality of 15 slots, means for engaging a slot to drive said registering mechanism independently of said pawls and a device controlling said lever and said last named means.

In testimony whereof, I affix my signature 20 in the presence of two witnesses.

RAY H. MANSON.
